UNITED STATES PATENT OFFICE

126,076

DESIGN FOR A BAROMETER

George B. Kimes, Kansas City, Kans.

Application October 17, 1940, Serial No. 95,901

Term of patent 14 years

To all whom it may concern:

Be it known that I, George B. Kimes, a citizen of the United States, residing at Kansas City, in the county of Wyandotte and State of Kansas, have invented a new, original, and ornamental Design for a Barometer, of which the following is a specification, reference being had to the accompanying drawing, forming part thereof.

In the drawing:

The figure is a perspective view of a barometer, showing my new design.

The back of the article is substantially plain.

I claim:

The ornamental design for a barometer, as shown and described.

GEORGE B. KIMES.
